UNITED STATES PATENT OFFICE.

WILLIAM HENRY ROUGHSEDE, OF OTTAWA, ONTARIO, CANADA.

MOLD FOR USE IN THE CONSTRUCTION OF CONCRETE BUILDINGS.

1,153,447.

Specification of Letters Patent. Patented Sept. 14, 1915.

Application filed June 10, 1911. Serial No. 632,810.

To all whom it may concern:

Be it known that I, WILLIAM HENRY ROUGHSEDE, of 64 Sparks street, in the city of Ottawa, county of Carleton, Province of Ontario, Dominion of Canada, have invented certain new and useful Improvements in Molds for Use in the Construction of Concrete Buildings, of which the following is a specification.

My invention relates to molds for use in the construction of concrete buildings, structures and walls of all kinds and the objects of my invention are, to provide a convertible and collapsible mold of the character described, which is economic and efficient and which may readily be adapted to form any part of the building whatever, to provide a mold rapidly, which is adapted to form the walls of the building all in one piece no matter how many stories may be included in the structure; to provide a mold which will form the walls of the building either solid or hollow as desired and which will permit of the erection of windows, doors, cisterns, tanks or other building necessities therein and finally to provide a mold which will render the rooms formed thereby less susceptible to the lodgment of dust.

In brief, my invention consists of a model, comprising a series of wings which extend parallel with each other and are jointed at intervals in a novel manner so that they may be extended to form a continuous wall or bend at right angles to each other to accommodate corner construction.

In the formation of hollow walls, a collapsible mold is introduced which is kept integral by the temporary insertion of novel locking means. All of these models are collapsible and are supported by certain novel devices which will be hereinafter more particularly described in the accompanying specification and drawings of which:

Figure 1 represents a plan view of my improved mold as applied to corner wall construction. Fig. 2 a perspective view of portion of the core mold with part of the locking device secured thereto. Fig. 3 is a similar view showing the other part of the device. Fig. 4 is a side view partly in section of the standards employed. Fig. 5 a sectional view on the line 3—3 Fig. 1, Fig. 6 a sectional view on the line 2—2 Fig. 1. Fig. 7 a sectional view on the line 4—4 Fig. 1. Fig. 8 a side view of my mold as ap-

plied to window or door formation. Fig. 9 a sectional view of the same on the line 5—5 of Fig. 8. Fig. 10 is a perspective detail of the clamp for the window mold. Fig. 11 is a sectional view along the line 6—6 of Fig. 8.

Referring to the drawings it will be seen that the mold in its construction comprises an outer member A and an inner member B adapted to mold the outer and inner surface of the wall respectively. It will be appreciated, however, that certain features of the invention might be applied to a mold member which is applied to mold only one surface of a wall. Each member consists of two wall members adjustably in angular relation to each other in order that they may be readily removed from the wall or other structure after the molding is applied and the concrete is set, thus the outer member A comprises wall members H and I which are pivotally supported from a cylindrical standard or post 10.

As illustrated the standard is tubular in form and the wall members have wiping contact therewith. The particular form of connection illustrated between the wall member and the standard comprises cores 11 in the end of the standard having pivot pins 12 at the top thereof formed with and fitting into the threaded sockets in the cores, said pivot pins extending through hinged members 13, which hinge members have flanges 14 which embrace parallel retaining plates 15 which are supported by a spacing member 16, which latter may be conveniently formed of wood.

The plates 15 form sockets in which the elements to mold the wall are adapted to be held, these elements are conveniently in the form of planks 18 which are adapted to abut each other and may if desired have dovetail or inclined contact with each other. These planks will vary in size to suit the nature of the structure to be molded and it will be appreciated that where the mold is to be used in isolated location the planks may be very readily shaped and fitted by the user of the mold.

In order to hold the mold members exactly at right angles to each other, bolts 20 may be provided extending through the hinge members into suitable sockets 19 in the ends of the cores. It will be noted that the angle of the corner to be molded may be varied by changing the position of the sock-

ets; this is not so important where the mold is used in house construction as it would be where a concrete retaining wall or the like is being constructed.

5 The inner member B is similar in general construction to the outer member. In order, however, to adapt both wall elements on this member for the molding of a perfectly straight wall the hinge members 13^a have 10 their outer portions bent at angles to the radius in such a way that the wall members may be swung around into alinement with each other and having their outer surface extending substantially tangential to the 15 standard.

To provide for the formation of a hollow wall, where desired, a core member C may be provided. This must necessarily be of a 20 collapsible character and must have a corner member of a similar character.

The embodiment of the core member illustrated comprises a pair of longitudinally extending corner guides 21 which are adapted to be spread by a spreading member D which has a screw threaded portion 28 25 adapted to engage partially the cylindrical screw threaded bores 23 formed in projections 22 on the guides. It will be seen that when the pointed extremity of the tightened member is engaged with the bores and turned it will spread the guides and retain them in spread position.

Spaced and parallel plates 29 are adapted 30 to fit the guide members and may conveniently extend in recesses 24 and 27 thereon; the recesses 27 being formed at the rear of wings 26. The plates are adapted to be releasably held in spaced relation by means of pairs of lugs 34 adapted to receive locking rods 35, the height of lugs being less than the normal distance between the plates 35 whereby the plates may collapse together when the rods are withdrawn. The space 40 between the plates 29 is divided by means of division plates 31 secured to blocks 30 on one side of the plates. It will be seen that the 45 three plates form sockets in which wall members 33, in the form of planks, may be held.

50 After the concrete has hardened in the space 43 between the mold and core member it is necessary to spring the same slightly to loosen the planks from the concrete and this may be accomplished through the use 55 of vertically extending rods 44 which are all substantially cam shaped in cross section and adapted when turned to spread the plank on opposite sides of the core.

If it is desired to have additional support 60 for the sides of the mold during casting, spacing members 36 may be provided having sharp edges which contact with the surface of the core and wall respectively together with supporting member 37 on the 65 exterior which may be driven into or con-

nected to the ground or floor beneath the mold; the upper end of said supports being connected by a tightening brace; the form of brace illustrated comprising a ring 41 connected to one support and loop 38 encircling the opposite support and a link 39 between the ring and loop and including a turn-buckle 40. It is of course obvious that if desired this additional supporting means might be omitted. When the mold is to be used for molding a complete house it will be necessary to provide means for the windows and doors and these are of similar construction.

In Figs. 8 to 11, I have shown a form of mold adaptable for a window. This mold comprises the side plates 46 forming sockets 47 to receive the planks 48; said plates being retained in position by means of spacing plates 51 adapted to mold the inner surface of the sides of the window or door opening and straps 55 having turned ends to engage the outer surface of the plates 46 on opposite sides of the wall, said straps being formed with eyes 56 through which locked bolts 53 may extend. These bolts also serve to retain the ends of the core mold in spaced relation the plates 29 of the core mold being formed with eyes 52 to receive the bolts. The outer ends of the straps are also formed with perforations through which bolts 50 extend into planks 49 provided on the plates 46. It will be seen that when the bolts 50 and 53 are loosened the walls of the window molds may be collapsed and the top of the window mold is adapted to be formed by a member 57 and the bottom by means of a collapsible wedge member 58. This wedge member consists of two parts 60 and 61 separated a short distance by screws 62 which fit in suitable screw threaded portions on said member. The upper member 60 being provided with plates 63 and 64 which overlap the other member and prevent the concrete passing between the members.

In using the mold, the wall members are set up as previously described and the core members, window molds and door molds set in position. To protect the iron work of the molds from adhesion of concrete oiled paper 42 or similar material may be placed against the same. The boards used in the forms of the mold members are desirably soaked in oil before use. When the various parts are thus set up the concrete is poured in and allowed to set. Before the setting is complete any spacing members 36 which have been inserted are tilted slightly and withdrawn. After setting, the wall members are loosened and those on the outer member are swung outwardly. The core member is then collapsed by withdrawing the rods 35 and tightening member D and loosening the planks 33 by turning the members 44 as previously described.

The mold is adapted for use in any form of concrete structures, and will enable any one flat or story of a dwelling house to be cast in one piece. It will also enable the 5 hollow walls to be constructed in the dwelling and if desired concrete walls, hollow or otherwise, for any purpose may be formed by its use. Particular attention is called to the jointed corner mold which enables the 10 wall molding elements to be swung around from the surface of the wall after casting. It will be seen also that the cylindrical standards produced a partially cylindrical surface at each corner and thus the interior 15 of the room will have practically an unbroken surface and this minimizes a lodgment of dust or dirt of any kind. If desirable a similar curved joint might be made between the floor and the wall. In addition 20 to the advantage of preventing accumulation of dust this curved arrangement adds substantially to the structure. It will also be noted that the cavity provided by the use of the core mold adjacent to the window 25 opening will conveniently accommodate sash weights. It is believed that the use of the present invention will enable a concrete house to be produced which will be proof against vermin, wind, frost, sound and fire. 30 As many changes could be made in the above construction and many apparently widely different embodiments of my invention, within the scope of the claims, constructed without departing from the spirit 35 or scope thereof, it is intended that all matter contained in the accompanying specification and drawings shall be interpreted as illustrative and not in a limiting sense.

What I claim as my invention is:

40 1. In a concrete mold and in combination, a pair of outer corner members, means for adjustably connecting said outer corner members together, means on each of said outer corner members adapted to loosely receive a plurality of planks or the like which are adapted to be used to mold the wall of the building, a pair of inner corner members, means for adjustably connecting the inner corner members together, and means 45 on each of the inner corner members for holding a plurality of planks or the like, and a collapsible core member comprising a collapsible corner member and loosely held wall molding members held by the collapsible corner members and cam means for expanding the collapsible core member.

2. In a concrete mold and in combination, a pair of outer corner members, means for adjustably connecting the same together, 50 sockets on each of the outer corner members adapted to receive a plurality of planks

which are adapted to mold the outer surface of the wall of the building, a pair of inner corner members, means for adjustably connecting the inner corner members together, 65 sockets on said inner corner members adapted to receive a plurality of planks for molding the inner walls of the building and a collapsible core member comprising a corner member having sockets to receive planks 70 or the like and cam means for expanding the collapsible core member.

3. In a concrete mold of the character described, a corner standard adapted to mold the corner, a socket member peripherally adjustable thereon and adapted to receive boards or the like which will mold the 75 surface of the wall.

4. In a concrete mold, a corner post adapted to mold the corner and a pair of angular adjustable socket members supported therefrom and wall molding members held in the socket members.

5. In a concrete mold and in combination, a tubular standard adapted to mold corners 85 and having cores at each end, socket members pivoted to the cores and including spaced plates and molding members held between the spaced plates.

6. In a concrete mold, a core member 90 comprising a corner section formed with parallel guides, means for spreading the guides comprising partially cylindrical screw threaded bores on each guide and a threaded spreading member adapted to engage said bore.

7. In a concrete mold, a core member comprising corner guides adapted to extend parallel to each other, means for spreading the guides at the corner thereof, comprising 100 a screw threaded spreading member having engagements with each guide, and parallel molding members held in the guides on each side of the corner.

8. In a concrete mold and in combination, 105 a wall member, a collapsible core, a collapsible door or window mold and a spreading member for the core extending through door or window mold.

9. In a concrete mold, and in combination, 110 a wall member, a collapsible core, a collapsible door or window mold and a spreading member for the core extending through the door or window mold and serving to spread the core mold and hold the 115 window or door mold together.

In witness whereof I have hereunto set my hand in the presence of two witnesses.

WILLIAM HENRY ROUGHSEIDGE.
